UNITED STATES PATENT OFFICE.

JOSEF KARRER, OF ZURICH, SWITZERLAND, ASSIGNOR TO MASCHINENFABRIK OERLIKON, OF OERLIKON, NEAR ZURICH, SWITZERLAND, A CORPORATION OF SWITZERLAND.

MULTIPLE-STAGE PRESSURE-STAGE TURBINE.

Application filed February 19, 1920. Serial No. 359,801.

(GRANTED UNDER THE PROVISIONS OF THE ACT OF MARCH 3, 1921, 41 STAT. L. 1813.)

To all whom it may concern:

Be it known that I, JOSEF KARRER, a citizen of the Swiss Republic, residing at Zurich, in the Republic of Switzerland, have invented certain new and useful Improvements 5 in Multiple-Stage Pressure-Stage Turbines (for which I have filed applications in Switzerland, patented 16th September, 1919, numbered 82,314; Great Britain, patented 10 23d June, 1921, numbered 138,597; Belgium, patented 15th March, 1920, numbered 284,928; France, patented 14th September, 1920, numbered 507,362; Germany, patented 16th February, 1921, numbered 332,959; Czechoslovak Republic, patented 3d June, 1921, numbered 5,336; Italy, patented 11th July, 15 numbered 523,35), of which the following is a specification.

This invention relates to improvements in 20 multiple-stage pressure-stage turbines.

In multiple-stage pressure-stage turbines all the stages are calculated for the same quantity of steam, and these turbines attain 25 their highest efficiency at full load, that is to say with the quantity of steam on which the calculation of the design was based. Under partial load the efficiency diminishes because, in consequence of the reduced quantity of steam, the conditions of flow no longer correspond to the design. Shutting off the 30 steam ducts of the individual stages in accordance with the load has been found too difficult and expensive, especially because—owing to the considerable distance separating the stages in consequence of the interposition of the regulating devices—the effluent velocity to the stages is lost, and the efficiency is thereby impaired. Consequently 35 the practice has been adopted of regulating the first pressure stage only—which may, itself, consist of several velocity stages—and this type of construction is at present widely used, especially in velocity-stage turbines.

Overload in steam turbines is generally 40 met by supplying auxiliary live steam to the low pressure stages, for which steam no allowance is made in calculating the ducts. The pressure of the live steam sinks to that 45 existing in the stage to which it is supplied, the heat-drop of the high-pressure stages 50 not being utilized so far as the auxiliary steam is concerned. Consequently, the effi-

ciency of the turbine sinks so much the more in proportion as it is overloaded. In velocity-stage turbines, or in pressure-stage 55 turbines with only a single high-pressure stage, it is, of course, possible to provide auxiliary ducts for the overload; and in such case the high-pressure heat drop is more or less satisfactorily utilized. Such turbines 60 work advantageously, even with overload. It is also known that velocity-stages have a considerably lower efficiency than pressure stages in the case of medium and large outputs. Nevertheless, velocity stages are 65 largely employed in high-pressure nowadays, the probable reason being their favourable behaviour in cases of overload. By reason of the high initial pressure, the use of only one high-pressure stage is generally disadvantageous, and therefore, in pressure-stage turbines, the auxiliary live steam, in case of 70 overload, is admitted at the end of the high-pressure stages, utilization of the high-pressure heat drop being dispensed with.

The present invention enables the steam to be favourably utilized at overload and partial load, in the case of pressure-stage turbines as well. According to the invention, 75 in a multiple-stage pressure stage steam turbine, which is provided with auxiliary ducts in addition to the guide ducts, calculated for a particular quantity of steam, the steam introduced through the auxiliary ducts does not flow immediately from the first stage or 80 one of the first stages into the succeeding stage, but is first diverted outward (radially), and is then admitted centripetally to one of the subsequent stages. In this stage the heat drop can then be further 85 utilized. Moreover one or more stages may be passed over. Furthermore, a stop valve or the like, which is only opened in the event of an overload, may be provided between two 90 overload stages.

In the accompanying drawings, showing 95 an embodiment of my invention, Fig. 1 is an axial section of the new multiple-stage pressure-stage turbine.

Fig. 2 is a section along the lines 2—2 100 of Fig. 1, the lower half of the section of Fig. 2 being taken through the steam admission to the guide ducts.

Live steam is admitted from the main in-

let valve to the regulating piston valve 1 (Fig. 2), where it is more or less throttled according to the load up to full load. The annular channel 2 does not supply the entire circumference; the nozzle chest 3 is calculated for the normal quantity of steam at full load. The steam passes through the partially supplied high pressure portion consisting of three stages, and reaches by way of the transition chamber 4, the fully supplied low pressure group of stages.

For guiding the overload steam, auxiliary channels are provided in the first and third stages. They, however, are not supplied up to full load, the two valves 5 and 6 shutting off the admission of steam. As soon as the turbine is overloaded or as soon as the normal quantity of steam is not sufficient to carry the desired load, the two overload valves open automatically. The regulating lever 7 bears, by means of the adjustable screw 8 against the relay piston 9, which becomes displaced downwardly so that the second overload valve 6 is entirely opened by oil under pressure. After the screw 8 abuts against the casing of the relay piston, it becomes the fulcrum of the regulating lever 7, and the first overload valve 5 becomes opened as far as is required against the opposition of the spring 10. The overload steam issuing from the annular channel 2 through the valve 5 reaches the inlet channel 11, from whence it passes by way of the nozzle chest 12 through the first rotor, and being diverted outwardly, passes through the open second overload valve 6 to the auxiliary chest 13 in the third stage, and does useful work in the third rotor, and thereupon mixes in the annular space 4 with the normal quantity of steam, to flow onwards through the low pressure portion. The overload steam works only in the first and third stages; the heat drop of the high pressure portion, however, is smaller with overload than with full load, inasmuch as the pressure in the transition space increases in accordance with the larger amount of steam. For this reason the high pressure heat drop of the auxiliary steam can be fully exploited in two stages.

The invention ensures economical running with overloads, and also enables increased economy to be obtained in the case of partial loads. This is effected by calculating the normal high-pressure ducts for a smaller quantity of steam than the low pressure stages, e. g. for 70 per cent of the nominal normal output. The high-pressure aggregation operates most favourably with a 70 per cent load, and more favourably with all smaller loads than if the high-pressure stage were calculated for 100 per cent load. At full load the low-pressure aggregation operates at its best, and owing to the favourable method of distributing the auxiliary

steam, the high-pressure aggregation still continues to work favourably, so that, with loads of 70-100 per cent, the steam consumption of the turbine is just as satisfactory as in the usual types, and even better than these in the case of smaller loads. Machines constructed in this manner also work very favourably with overloads, if further overload ducts be introduced.

It is not essential that the auxiliary live steam should be supplied to the first stage; and the turbine may also consist of any desired number of stages and groups of stages, and of velocity stages and pressure stages; and, indeed, the invention can be applied to any type of construction. The operation of the auxiliary valves may be effected by hand or automatically.

What I claim as new and desire to secure by Letters Patent is:—

1. In a multi-stage pressure-stage turbine, a group of high-pressure stages, guide ducts of normal capacity partially supplying and permanently interconnecting said stages of said group, auxiliary guide ducts partially supplying a stage of said group, means for controlling the steam supplied by said auxiliary guide ducts to said stage, auxiliary guide ducts partially supplying a subsequent stage of said group, means for diverting steam from said first-mentioned stage to said auxiliary guide ducts of said subsequent stage and means for controlling the flow of steam from said first-mentioned stage along said diverting means to said auxiliary guide ducts of said subsequent stage.

2. In a multi-stage pressure-stage turbine, a group of high-pressure stages, guide ducts of normal capacity partially supplying and permanently interconnecting said stages of said group, auxiliary guide ducts partially supplying an early stage of said group, means for controlling the steam supplied by said auxiliary guide ducts to said early stage, auxiliary guide ducts partially supplying a remote subsequent stage of said group, means for diverting steam from said early stage past an intermediate stage to said auxiliary guide ducts of said remote subsequent stage and means for controlling the flow of steam from said early stage along said diverting means to said auxiliary guide ducts of said remote subsequent stage.

3. In a multi-stage pressure-stage turbine, a group of high-pressure stages, guide ducts of normal capacity partially supplying and permanently interconnecting said stages of said group, auxiliary guide ducts partially supplying the first stage of said group, means for controlling the steam supplied by said auxiliary guide ducts to said first stage, auxiliary guide ducts partially supplying a remote subsequent stage of said group, means for diverting steam from said first stage past an intermediate stage to said auxiliary guide

ducts of said remote subsequent stage and means for controlling the flow of steam from said first stage along said diverting means to said auxiliary guide ducts of said remote 5 subsequent stage.

4. In a multi-stage pressure-stage turbine, a group of high-pressure stages, guide ducts of normal capacity partially supplying and permanently interconnecting said stages of 10 said group, auxiliary guide ducts partially supplying a stage of said group, a valve controlling the steam supplied by said auxiliary guide ducts to said stage, auxiliary guide ducts partially supplying a subsequent stage 15 of said group, a passage leading from said first-mentioned stage to said auxiliary guide ducts of said subsequent stage and a valve controlling the flow of steam from said first-mentioned stage along said passage to said 20 auxiliary guide ducts of said subsequent stage.

5. In a multi-stage pressure-stage turbine, a group of high-pressure stages, guide ducts of normal capacity partially supplying and 25 permanently interconnecting said stages of said group, auxiliary guide ducts partially supplying an early stage of said group, a valve controlling the steam supplied by said auxiliary guide ducts to said early stage,

auxiliary guide ducts partially supplying 30 a remote subsequent stage of said group, a passage leading from said early stage past an intermediate stage to said auxiliary guide ducts of said remote subsequent stage and a valve controlling the flow of steam from said 35 early stage along said passage to said auxiliary guide ducts of said remote subsequent stage.

6. In a multi-stage pressure-stage turbine, a group of high-pressure stages, guide ducts 40 of normal capacity partially supplying and permanently interconnecting said stages of said group, auxiliary guide ducts partially supplying the first stage of said group, a valve controlling the steam supplied by said 45 auxiliary guide ducts to said first stage, auxiliary guide ducts partially supplying a remote subsequent stage of said group, a passage leading from said first stage past an intermediate stage to said auxiliary guide 50 ducts of said remote subsequent stage and a valve controlling the flow of steam from said first stage along said passage to said auxiliary guide ducts of said remote subsequent stage. 55

In testimony whereof, I affix my signature.

JOSEF KARRER.
